UNITED STATES PATENT OFFICE.

GIDEON B. MASSEY, OF MOUNT VERNON, NEW YORK, ASSIGNOR OF ONE-THIRD TO LOUIS A. GARNETT, OF SAN FRANCISCO, CALIFORNIA.

SPRING SHADE-ROLLER.

SPECIFICATION forming part of Letters Patent No. 299,239, dated May 27, 1884.

Application filed October 23, 1883. (No model.)

To all whom it may concern:

Be it known that I, GIDEON B. MASSEY, of Mount Vernon, in the county of Westchester and State of New York, have invented a new and useful Improvement in Spring Shade-Rollers, of which the following is a full, clear, and exact description.

If a window-shade secured to a spring shade-roller of the usual construction is suddenly released, the spring revolves the roller with great rapidity, and the shade is wound on the roller, the bottom stick of the shade is carried around the roller, the cord attached to the shade is wound around the roller, and the spring in the roller is entirely uncoiled, thereby causing inconvenience and necessitating the unwinding of the cord and the readjusting of the roller.

The object of my invention is to provide a new and improved spring shade-roller which is so constructed that when the shade is suddenly released the roller will be checked and will be prevented from winding up the shade too far.

Reference is to be had to the accompanying drawings, forming a part of this specification, in which similar letters of reference indicate corresponding parts in all the figures.

Figure 1 is a longitudinal elevation of my improved spring-roller and a window-shade attached to the same, parts being broken out and others shown in section. Fig. 2 is a cross-sectional elevation of the same on the line *xx*, Fig. 1, showing the position of the roller when it is locked. Fig. 3 is a cross-sectional elevation of the same on the line *yy*, Fig. 1, showing the roller when it is unlocked. Fig. 4 is an end view of the roller.

The spring shade-roller *A* is provided at one end with a ratchet-wheel, *B*, in the usual manner, and with end pivots, *C* and *C'*, of which the former extends into a vertical slot, *D*, formed in a plate, *E*, secured in the window-casing. A bent spring, *F*, secured to the window-casing, has its free end resting against the bottom of the pivot *C*, thus pressing the same upward. A pawl, *G*, is pivoted to the window-casing in such a manner that

its free end can rest on the teeth of the ratchet-wheel *B*, which pawl *G* is pressed upward by 50 a bent spring-wire, *H*, secured to the window-casing, the free end of the said spring-wire being bent under the pawl *G*, so as to press the pawl upward against a stud, *J*, projecting from the window-frame. In place of the bent 55 spring-wires *F* and *H*, band-springs or spiral springs can be used.

The operation is as follows: If the shade *K*, secured to the roller *A*, is to be unwound, the shade is pulled downward and the strain on 60 the shade draws the shade-roller downward, whereby the spring *F* will be pressed downward and the ratchet-wheel *B* will be disengaged from the pawl *G*, thus permitting the roller to revolve in such a manner as to unwind the shade. As soon as the shade is released the spring *F* presses the pivot *C* upward, thereby engaging the end of the pawl *G* with the teeth of the ratchet-wheel *B*, whereby the roller will be locked in position. If 65 the window-shade is to be raised—that is, wound on its roller—the shade is pulled downward slightly, so as to disengage the ratchet-wheel *B* from the pawl *G*, and then the strain on the shade is diminished, so as to permit the 70 roller to revolve; but the strain must still be sufficient to keep the spring *F* depressed and the ratchet-wheel *B* lowered to such an extent that the ratchet-wheel cannot engage with the pawl. If the shade-cord breaks or the shade 75 is released suddenly, it will not be wound on the roller with great rapidity, as the spring *F* will throw the pivot *C*, the ratchet-wheel *B*, and the corresponding end of the roller upward as soon as the shade is released, thus engaging the ratchet-wheel with the pawl *G* and locking the roller in place; or, in other words, the shade can only be wound on the roller as long as there is sufficient strain on the shade to keep the spring *F* depressed, and as soon 80 as the shade is entirely released the strain is removed and the roller is locked in position, whereby the roller is prevented from raising the shade too rapidly and tearing the shade or winding the cord on the roller, and at the 85 same time the entire uncoiling of the spring

in the roller is prevented. The pivot C is connected with the spring in any suitable manner.

Having thus described my invention, I claim as new and desire to secure by Letters Patent—

- 5 1. The combination, with a spring shade-roller, of a spring for pressing the end provided with a ratchet-wheel upward, a pawl adapted to engage with the ratchet-wheel, and a spring for holding the pawl raised to a certain position, substantially as herein shown and described.

2. The combination, with a spring shade-roller, of a spring for pressing the end provided with a ratchet-wheel upward, the pawl G, adapted to engage with the ratchet-wheel, the 15 check-stud J, and the spring H, for drawing the pawl against the stud J, substantially as herein shown and described.

GIDEON B. MASSEY.
